UNITED STATES PATENT OFFICE.

MORGAN C. FRENCH, OF CRAIG, COLORADO.

BRUSH-PLOW.

1,184,847.

Specification of Letters Patent. Patented May 30, 1916.

Application filed July 7, 1915. Serial No. 38,412.

To all whom it may concern:

Be it known that I, MORGAN C. FRENCH, a citizen of the United States, residing at Craig, in the county of Moffat and State of Colorado, have invented certain new and useful Improvements in Brush-Plows; and I do hereby declare the following to be a full, clear, and exact description of the invention, such as will enable others skilled in the art to which it appertains to make and use the same.

My invention relates to new and useful improvements in brush plows, and is more particularly an improvement over my former Patent No. 1,153,213, issued September 14, 1915, and my object is to provide suitable disintegrating disks in connection with the plow and means to rotate the same.

A further object is to provide means for clearing a path for the main driving wheel. And a further object is to provide means for regulating the operation of the mold board.

Other objects and advantages will be hereinafter set forth and more particularly pointed out in the accompanying specification.

In the accompanying drawings which are made a part of this application, the figure is a perspective view of parts of a brush plow, showing my improved attachment applied thereto.

In the drawings 1 indicates a beam of any preferred construction, depending from which are standards 2 and 3, the lower ends 35 of said standards carrying a land side 4, the forward end of the land side being tapered downwardly to a point and carrying a mold board 5.

Extending rearwardly from the rear edge 40 of the mold board 5 are a plurality of fingers 6 which are adapted to carry portions of the soil and roots, brush and the like, loosened by the mold board into the path of a plurality of cutting disks 7, which disks 45 are adapted to disintegrate the solid particles of the soil and to cut into short lengths roots, brush and the like coming in contact with the disks.

The disks are mounted upon a shaft 8, 50 which extends transversely of the path of the mold board, and there is preferably a disk positioned between each pair of fingers, the shaft 8 being mounted in a suitable sup-

port 9. Secured to one end of the shaft 8 is a beveled gear 10 which meshes with a 55 similar gear 11 attached to one end of a tumbling shaft 12, said shaft extending through a bearing 13 on the landside.

The tumbling shaft is constructed in sections, the section 14 being mounted in a 60 bearing 15 and having a bevel gear 16 which meshes with a bevel driving gear 17 carried by an auxiliary beam 18, the opposite end of the section 14 having a universal joint 19 which connects the section 14 to a socket 65 member 20. The section 21 of the tumbling shaft 12 also extends through a bearing 22 on the standard 3 in addition to extending through the bearing 13, the end of the section 21 having a universal joint 23 which 70 connects the same to a section 24, said section 24 having a squared portion 25 which connects with the square opening of the socket member 20 and is adjustable therewith so that the raising and lowering of the 75 mold board and parts carried thereby will not interfere with the operation of the tumbling shaft.

Rotatably mounted in the rear end of the auxiliary beam 18 is a drive wheel 26 which 80 has attached thereto a cog wheel 27 which meshes with a cog wheel 28 attached to the shaft 29 carrying the driving gear 17, and it will be readily seen that as the plow travels forwardly, the driving wheel will 85 impart rotating motion to the disks 7 through the various gears and tumbling shaft as described.

The operation of the various gears is controlled through the medium of a gear shifting lever 30 which may be constructed in any preferred manner for shifting one of the gears out of mesh with its co-operating gear to stop the operation of the disks 7.

The forward end of the auxiliary beam 95 18 is pivotally attached to the beam 1 adjacent the forward end thereof, said auxiliary beam extending through a link 31 carried at the rear end of the beam 1, the lower end of said link having an arm 32 to which is attached one end of a coil spring 33, the opposite end of said spring being attached to a hanger 34 carried by the auxiliary beam 1, the tension of said spring being such as to normally hold the mold board at a proper 100 level and provide yielding movement of the

mold board with respect to the auxiliary beam, so that when an obstruction is encountered, the mold board may arise or descend without affecting the rear end of the auxiliary beam.

In order to positively elevate the mold board to disengage the same from the soil, a lever 35 is pivotally attached to the auxiliary beam 18, one end of said lever 10 being attached to the arm 32 of the link 31 by means of a rod 36, one end of which is pivotally attached to the end of the lever 35 and the opposite end pivotally attached to the arm 32, and it will be readily seen 15 that when the free end of the lever is thrown downwardly, the rear end of the beam 1 and the mold board carried thereby will be elevated.

In order to provide a solid foundation for 20 the travel of the drive wheel 26, a sub mold board 37 is attached to the land side 4 adjacent the rear end thereof, said sub mold board traveling in the rear of the mold board 5 so as to encounter the soil loosened by the mold 25 board to move the soil out of the path of the driving wheel, the sub mold board having a rearwardly extending shank 38 between which and the outer end of the sub mold board is extended a brace 39.

To insure that no foreign particles, such 30 as brush, trash, and the like, will come in engagement with the drive wheel 26 or the gear carried thereby, a shield 40 is placed forwardly of the drive wheel and at an 35 angle to the path of the plow, the upper end of the shield being attached to the auxiliary beam 18, while the lower end thereof is attached to the shank 38.

Positioned forwardly of the mold board 40 5 is my improved form of colter 41, which is preferably curved from end to end and describes substantially an arc of a circle, the upper end of the colter being pivotally attached to a bolt 42, which is in turn secured 45 to the beam 1, the lower rearward edge of the colter having serrations to form cutting teeth 43 so that the colter will more readily sever roots, brush and trash coming in the path thereof.

In order to permit the lower end of the colter to swing upwardly when a stone or other solid object is encountered, a rod 44 is 50 pivotally attached to the lower end of the colter and extended upwardly through the beam 1 and through a clevis 45 mounted above the beam, the extreme upper end of the rod 44 being threaded to receive a nut 46, by means of which the position of the colter may be adjusted.

The colter is normally held in its lowered 60 position by means of a spring 47 which extends around that portion of the rod 44 between the beam and the clevis, the lower end of the spring resting upon a collar 48 fixed

to the rod 44, and the upper end thereof 65 with that portion of the clevis through which the rod extends, the tension of the spring being such as to hold the colter in its lowered position under all ordinary circumstances, but should a solid object be encountered through which the colter cannot pass, it will rise upwardly and pass over the obstruction without affecting the position of the mold board. The colter is also provided 70 with a pair of wings 49 which extend rearwardly and outwardly from the colter and are adapted to separate the brush or other obstructions and move the same out of the line of the path of the cutting bar or colter 75 50 attached to the land side and beam adjacent the forward edge of the mold board, thus preventing any foreign particles from 80 coming in contact with and collecting against the cutting bar or standards.

This form of plow is adapted primarily 85 for use in loosening soil having growing brush and shrubbery thereon, and in operation the free end of the lever 35 is thrown upwardly, thus lowering the mold board 5 in position to enter the soil. The plow is 90 then moved forwardly through any suitable source, the colter 41 severing the roots and brush in advance of the mold board, and moving particles thereof above the soil to one side of the path of the cutting bar and 95 standards of the plow, while the mold board loosens the soil to the width of the mold board, the forward travel of the plow causing the soil, so loosened, to travel over the fingers 6 and into engagement with the plurality of disks 7 mounted therebetween. As 100 the disks are rotated, the cutting edges thereof will engage any roots or brush contained in the soil and cut them into short lengths, so that the severed portions thereof 105 will not interfere with the cultivation of the soil.

As the plow moves forwardly, the soil loosened by the mold board 5, after passing beyond the fingers 6 will be encountered by 110 the sub mold board 37 and the shield 40 and removed to one side of the path of the drive wheel 26 so that said drive wheel will rest upon the solid bottom of the furrow, thus causing the wheel to positively rotate as the 115 plow is moved forwardly.

When the plow is to be moved from place to place, the lever 35 is thrown downwardly until the plow is moved to a point above the soil, and said lever may be secured in 120 its lowered position in any suitable manner, thereby holding the plow out of engagement with the soil until the lever is again elevated.

Having thus fully described my invention 125 what I claim as new and desire to secure by Letters Patent of the United States is:—

1. In a plow of the class described, the

combination with a mold board, cutting disks coöperating with said mold board, a driving wheel, and means coöperating with the driving wheel and disks to rotate said 5 disks, of a sub-mold board in the path of the first mold board adapted to remove the soil loosened by the first mold board from the path of the driving wheel.

2. In a brush plow, the combination with 10 a beam and a mold board carried thereby, of an auxiliary beam pivoted at one end to said first beam and adjacent the forward end thereof, a driving wheel carried by the auxiliary beam, a link carried by the first beam 15 through which said auxiliary beam extends, a resilient connection between said link and the auxiliary beam, and a lever for elevating the first beam and the mold board carried thereby.
- 20 3. In a brush plow, the combination with a mold board and a driving wheel in the path of said mold board, of a sub mold board between said driving wheel and first mold board, and a shield forwardly of the 25 driving wheel adapted to remove rubbish

and the like from the path of the driving wheel.

4. In a brush plow, the combination with a beam and a mold board carried thereby, of an auxiliary beam pivotally secured at 30 its forward end to the forward portion of the first beam, a driving wheel carried by the auxiliary beam, a link attached to the rear end portion of the first beam through which said auxiliary beam extends, an arm 35 at the lower end of the link, a hanger on said auxiliary beam, a spring connecting said hanger and arm to resiliently support the rear end of the beam, and a lever connected to said arm and pivoted to the auxiliary beam to raise said first beam and the mold board carried thereby.

In testimony whereof I have signed my name to this specification in the presence of two subscribing witnesses.
